UNITED STATES PATENT OFFICE.

POINDEXTER HILL, OF BETHESDA, ARKANSAS.

BOAT.

1,380,296.

Specification of Letters Patent. Patented May 31, 1921.

Application filed August 16, 1920. Serial No. 403,718.

To all whom it may concern:

Be it known that I, POINDEXTER HILL, a citizen of the United States, residing at Bethesda, in the county of Independence 5 and State of Arkansas, have invented new and useful Improvements in Boats, of which the following is a specification.

This invention relates to boats and comprehends a construction wherein the hull of 10 the boat is made up of a plurality of hollow cylindrical bodies suitably connected to a motor utilized to rotate said bodies, the cylindrical bodies being equipped with blades or the like to promote propulsion, the boat 15 being particularly designed for speed.

One of the chief characteristics of the invention resides in the novel construction of means for steering the boat, which means embodies among other features a plurality 20 of rudders connected to the collars slidably mounted on a shaft, said collars being controlled through the instrumentality of a steering wheel which is connected to the collars through the instrumentality of a flexible 25 element.

The nature and advantages of the invention will be better understood when the following detailed description is read in connection with the accompanying drawings, 30 the invention residing in the construction, combination and arrangement of parts as claimed.

In the drawings forming part of this application like numerals of reference indicate 35 similar parts in the several views and wherein:

Figure 1 is a side elevation of the boat.

Fig. 2 is a plan view of the hull construction.

Fig. 3 is a sectional view taken on line 3-3 of Fig. 1.

Fig. 4 is a similar view taken on line 4-4 of Fig. 2.

Fig. 5 is an enlarged detail view of one 45 of the collars and rudders associated therewith.

Fig. 6 is a perspective view of one of the cylindrical bodies.

Referring to the drawings in detail, A indicates generally the boat construction in 50 accordance with my invention, and wherein the hull of the boat is made up of spaced parallel side members 10 and a plurality of hollow cylindrical bodies 11 which are journaled between the side members 10, and each member being equipped with a plurality of

angularly disposed blades 12 which materially assists the cylindrical bodies to effectively engage the water to promote propulsion. Rising from the side members 10 are 60 a number of diagonally disposed bracing elements 13 which support the floor 14 of the boat and upon which is mounted a motor at 15 of any suitable character. The motor includes a sprocket 17 over which is 65 trained a chain 18, the latter being also trained over a sprocket 19 as shown. The cylindrical bodies are driven from the motor as is obvious, an endless chain 19' being trained over sprockets 20 for this purpose, 70 the sprocket and chain being arranged inwardly of the side parallel members 10.

Slidably mounted upon the shaft 21 of the rearmost cylindrical body is a plurality of collars or the like 22, and each being 75 provided with an extension as shown. Rudders 23 for steering the boat are provided and connected together for simultaneous movement by means of a rod 24'. Each rudder post has associated therewith a lever 24 which is bifurcated at one end to receive the extension above referred to of the adjacent collar 22. The steering wheel is indicated at 26 and the flexible element 25 is trained about the steering wheel and 80 has its free extremities secured to the extensions of the collars as clearly illustrated in Fig. 4. Manifestly, by adjusting the steering wheel one or the other of the collars are moved upon the shaft 21, the extension of these collars actuates the associated lever 24 to adjust the rudders and consequently steer the boat in the proper direction. It is thereby understood that the cylindrical bodies 11 may vary in number 85 and size in a boat construction, this depending upon the size of the boat and the speed required.

While it is believed that from the foregoing description the nature and advantages 100 of the invention will be readily apparent, I desire to have it understood that I do not limit myself to what is herein shown and described and that such changes may be resorted to when desired as fall within the 105 scope of what is claimed.

What I claim is:—

1. In combination with a boat wherein the hull is made up of a plurality of hollow cylindrical bodies mounted for rotation, of 110 collars slidably mounted upon the shaft of one of said cylindrical bodies, a rudder con-

nected to each collar, a steering wheel, and a connection between the steering wheel and said slidable collars for effecting an adjustment of said rudders to steer the boat.

5. 2. In a boat of the buoyant propelled type comprising transversely disposed paddle wheels, in combination with the shaft of the rear paddle wheel, of collars slidably mounted upon said shaft, extensions connected with said collars to effect an adjustment of the latter, rudders connected to said collars for movement therewith, a steering wheel, and a flexible element connected be-

tween the steering wheel and said extensions for the purpose specified.

3. In a boat of the buoyant, propelling type comprising transversely disposed paddle wheels, in combination with the shaft of the rear paddle wheel, of rudders, means slidably mounted on the shaft and connected with the rudders and operating the latter, a steering wheel, and a connection between the steering wheel and said means for the purpose specified.

In testimony whereof I affix my signature.

POINDEXTER HILL.
